UNITED STATES PATENT OFFICE.

GEORGE H. POOR, OF ST. LOUIS, MISSOURI, ASSIGNOR TO THE AMERICAN BRAKE COMPANY, OF SAME PLACE.

LOCOMOTIVE-BRAKE.

SPECIFICATION forming part of Letters Patent No. 317,571, dated May 12, 1885.

Application filed July 23, 1884. (No model.)

To all whom it may concern:

Be it known that I, GEORGE H. POOR, a citizen of the United States, residing at St. Louis, in the State of Missouri, have invented 5 certain new and useful Improvements in Locomotive-Brakes; and I hereby declare the following to be a full, clear, and exact description of the same, reference being had to the accompanying drawings, wherein—

10 Figure 1 is a side elevation, partly in section, of a horizontal cylinder, brake-heads, &c., embodying my invention. Fig. 2 is a longitudinal central section of the cylinder. Fig. 3 is an end view of the same. Fig. 4 is a longitudinal central section of one of the pistons and its rings and follower. Fig. 5 is an end view of the same. Fig. 6 is a detached view of the piston-rod and push-bar. Fig. 7 is a modification thereof, showing a bend in 15 the piston, and adapted for use where the cylinder cannot be properly aligned with the brake-heads. Fig. 8 is a sectional view of a drip-valve for the cylinder. Fig. 9 is an end or bottom view of the same. Fig. 10 is a 20 view similar to Fig. 1, showing a modified manner of pivoting the hangers to the brake-head.

Like letters refer to like parts wherever they occur.

25 My invention relates to the construction and arrangement of that class of brakes which are applied to the drive-wheels of locomotives; and it has for its object, first, such an arrangement of the hangers and brake-heads 30 as will enable them to be applied to the best advantage where the distance between the drivers is considerable, or there are obstructions in the way of the hangers when pivoted on the bracket which supports the cylinder, 35 for which purpose I employ channel-plates or angle-iron brackets secured to the locomotive-frame, pivoting thereon the hangers by which 40 the brake-heads are suspended.

45 Another object I have in view is to compensate for the lost motion and permit of an adjustment between the push-bar and piston, for which purpose I provide a socket in the end of the push-bar for the reception of the end of the piston-rod, wherein liners may be 50 inserted, and with which a set-screw or other

holding device may be used to connect the parts.

There are a number of other features, mainly those of special construction, having practical value in this class of devices, which will 55 appear more fully hereinafter.

I will now proceed to describe my invention more specifically, so that others skilled in the art to which it appertains may apply 60 the same.

In the drawings, A A represent the wheels, between which the brakes are suspended, and to which they are to be applied; B B, the locomotive-frame, which affords the means for supporting the brakes. At suitable points, 65 either upon or between the frames B B, are secured the plates to which the hangers are pivoted, the points being determined by the distance between the wheels A A or the presence or absence of obstructions on the frames 70 B B. These hanger-supports may be either channel-plates C C, extending from the upper to the lower frame and bolted thereto, as shown in Fig. 1, or angle-irons C', mounted on the lower frame, (see Fig. 10,) and provided with bosses or lugs, c, upon which the 75 hangers are pivoted. This construction permits the points of suspension of the brake-heads to be adapted to circumstances, so as to 80 meet the requirements of any existing constructions in locomotives.

D D indicate the hangers for the brake-heads, pivoted on the bosses c of the hanger-plates C above and to the brake-heads E E below.

85 Secured to the frame B at a point midway between the wheels is an angle-iron bracket or flanged plate, F, for the support of the cylinder G, &c., by means of which the brakes are applied. The cylinder G is open at both 90 ends, or devoid of heads, and is cast or otherwise formed with a tangential flange, g, at its middle for securing it to the bracket F, a lip, g', for bracing it against the frame B of the locomotive, and a rib, g'', and fillets g'', 95 for strengthening the flange g. On the inner surface of the cylinder G, near the ends thereof, are circular grooves or channels g', which gather any water of condensation which takes place in the outer ends of the cylinder, which 100

moisture is allowed to escape through the channels g^5 , which may be made in projections G' on the lower outer surface of the cylinder.

5 In order to discharge the water of condensation from the cylinder between the pistons, the cylinder is provided at the middle and on its lowest side with a port controlled by an automatic drip-valve, H . The drip-valve H has a cylindrical shell, h , threaded above, so as to be screwed into the port of the cylinder, and below so as to receive a short pipe, which will carry the drip beyond the rail and prevent it from falling thereon. Arranged to seat 15 on the upper end of shell h is the valve h' , having a stem, h^2 , which projects centrally through the shell, and is secured by a cotter, h^3 . Within the shell and acting on the valve h' , the stem h^2 of which it surrounds, is a helical or 20 coiled spring, h^4 , which acts on the valve so as to force it off its seat when the valve is relieved of the pressure of steam in cylinder G . The stem h^2 is of such diameter as to leave a 25 passage through the shell for water from cylinder G , and the lower end of the shell can have a series of V-shaped slots or openings, h^5 , for like purposes. The stem h^2 , just below the valve h' , is provided with radial wings h^6 , which serve to center the valve and its stem 30 with the shell without obstructing the flow of the discharge or water of condensation.

I indicates the supply-pipe through which steam or air to operate the pistons is admitted.

K indicates the pistons, two of which are 35 employed. These pistons are hollow cylinders, open at one end and as shown in the drawings, and having therein a cup or ball socket, k , for the reception of one end of the piston-rod L . These pistons are provided at their inner ends 40 with ring-grooves for the packing-rings k' , and a follower, k^2 , for securing the packing-rings. The inner face of each piston, or that face against which the steam acts, is provided 45 with a truncated conical projection, k^3 , which prevents the pistons from coming in contact, except at those points, and thus preserves a steamway and a channel for the escape of the water of condensation.

L indicates the piston-rods, having at their 50 inner ends rounded surfaces to form, with the cups k of the pistons, a species of ball-and-socket joint, which will permit of the lateral motion or play of the piston-rods to compensate for the spring of the brake-head. The 55 outer ends of the pistons L enter sockets in the push-bars M .

M indicates the push-bar, which has a socket, m , at one end for the reception of the outer end of the piston-rod, and a set-screw, m' , for 60 connecting the push-bar to the piston. n indicates liners, which may be inserted between the bottom of socket m and the end of piston-rod L , to increase or decrease the reach of the combined piston-rod and push-bar, as circumstances may require. The push-bar is pivoted 65 to the brake-head E , as at m^2 , and is provided with a projection or toe, m^3 , arranged at such

an angle to the push-bar as shall bring it on a line parallel with a tangent of the drive-wheel, so that the set-screw m^4 of the toe will be effective to properly set the brake-head, with its shoe, up to the periphery of the drive-wheel. 70

In some instances it will be found impracticable to so set the horizontal cylinder G that its axis will be in line with the brake-heads 75 or in line with the axis of the push-bar M , in which case an elbow or bend, o , may be formed in the piston-rod, as shown in Fig. 7, to compensate therefor.

The devices, being substantially of the character specified, will operate as follows: Steam being admitted to the horizontal cylinder G through pipe I , first forces the drip-valve h down on its seat, and then, acting on the heads of the pistons, forces them apart, carrying out 80 the push-bars M and forcing the brake-heads E against the drivers. As the brake-heads E move in the arc of a circle or in a curved path, the inner end of the piston-rod rocks in its cup or socket, so as to maintain the direct line of 85 pressure, and as the toe of the push-bar is parallel to a tangent drawn from the periphery of the wheel, if the brake-head has been properly adjusted (by means of set-screw m^4) the shoe will be applied to the periphery of the 90 wheel at all points with uniform power. 95

When the steam-pressure is withdrawn from cylinder G , or sufficiently reduced therein to allow the spring h of the drip-valve to operate, the valve h will be lifted off its seat, thus opening an exhaust for any steam which may remain between the pistons, and also a drip or escape for any water of condensation. As the pistons move toward each other the faces of the truncated cone will meet, thus arresting 100 further inward movement and forming an annular steamway leading to the automatic valve, which facilitates the escape of the water of condensation, and causes the steam, when admitted, to act uniformly on the pistons, giving 105 them a quick and regular outward movement when the brakes are applied.

Any water of condensation deposited or escaping into the outer ends of cylinder G , instead of escaping therefrom at the most dependent portion and falling upon the track, will gather in the grooves or channels g^4 , and escape by channels g^5 , so as to fall clear of the rails. 115

By employing the channel-plates $C C$ or angle-irons $C' C'$ and bolting or otherwise securing them either between the frames $B B$ or on the lower frame B , the pivot of the hanger can be so placed with relation to the wheel and the brake-head that the path of the brake-head 120 will have the minimum curve, and thus enable the power to be applied from the cylinder G to the very best advantage.

I do not herein claim the construction of the cylinder and pistons, as the same forms 125 the subject-matter of an application filed December 9, 1884, Serial No. 149,873; neither do I herein claim the means for relieving the cylinder of the water of condensation, as the

same forms the subject-matter of another application filed December 9, 1884, Serial No. 149,867; but,

Having thus set forth the nature, advantages, 5 and operation of my invention, what I claim, and desire to secure by Letters Patent, is—

1. In a locomotive-brake, the combination, with a horizontal cylinder, direct-acting push-bars, and brake-heads actuated thereby, all arranged between the drive-wheels, of the independent channel-plates or angle-irons secured to the locomotive-frame and the hangers for suspending the brake-heads therefrom, substantially as and for the purposes specified. 10

15 2. In a locomotive-brake, the combination, with the piston-rod which actuates the brake-head, of a push-bar having a socket for the reception of the piston-rod, substantially as and for the purposes specified.

20 3. In a locomotive-brake, the combination, with the piston-rod which actuates the brake-head, of a push-bar having a socket for the reception of the end of the push-rod, and a liner or liners interposed between the end of the

25 piston-rod and the bottom of the socket of the push-bar, substantially as and for the purposes specified.

4. In a locomotive-brake, the combination, with a suspended brake-head, of a horizontal cylinder having a piston with a cup or socket 30 for the reception of the end of the piston-rod, a piston-rod having a round or ball end to form a ball-socket joint with the piston of the cylinder, and an adjustable push-bar, substantially as and for the purposes specified. 35

5. In a locomotive-brake, the combination, with a brake-head and a horizontal cylinder for operating the same, of an interposed rod having a curve or bend to compensate for lack of alignment between the cylinder and brake-head, substantially as and for the purposes specified. 40

6. A push-bar for locomotive-brakes having at one end a socket for the piston-rod and at the opposite end a toe or oblique projection 45 for a brake-head adjusting-screw, substantially as and for the purposes specified.

In testimony whereof I affix my signature, in presence of two witnesses, this 23d day of July, 1884.

GEORGE H. POOR.
